CLAIM

The ornamental design for a luminaire, as shown and described.

DESCRIPTION

FIG. 1 is a perspective view of a luminaire showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof, with the four arms shown pivoted to an alternate position;

FIG. 9 is an inverted perspective view of FIG. 8;

FIG. 10 is a perspective view thereof, similar to FIG. 8, but with the post portion shown extended vertically to an alternate position;

FIG. 11 is a perspective view thereof, with the four arms shown pivoted to another alternate position; and,

FIG. 12 is a perspective view thereof, with the four arms shown pivoted to yet another alternate position.
